UNITED STATES PATENT OFFICE

REINHARDT DAAE, OF YOUNGSTOWN, OHIO

BILLET FURNACE

Application filed May 3, 1929. Serial No. 360,031.

My invention relates to furnaces, and more particularly to billet furnaces, and to mechanism for advancing and withdrawing billets therefrom.

In billet furnaces as heretofore constructed, the floors of the heating chambers of the furnaces have generally been given slopes. Skids are provided on the floors and extend from the entrance of the furnace to a position near the discharge end of the furnace. When billets, and particularly cylindrical billets such as are used for forming tubes and pipes, are placed on these skids, the billets roll and slide down the skids partially under the influence of the force of gravity towards the discharge end. A discharge mechanism, generally in the form of a ram, discharges the billets with an endwise motion onto a run-off table.

As continued contact between the same areas on a billet and skids results in an uneven heating of the billets and the formation of dark or cold areas on the billets, it is customary to discharge the billets directly onto the floor of the furnace near its discharge end. Engagement with the furnace floor, which is maintained at a substantially uniform temperature, insures a substantially uniform heating of the billets.

Near the end of the furnace a discharge ram engages the billets and moves them longitudinally onto a run-off table. For assisting in the movement of the billets toward the discharge mechanism, a pusher is provided.

The pusher is movable along a track substantially paralleling one of the faces of the furnace. A pusher bar is insertable into doors spaced along the furnace for advancing the billets when they stick on the skids or the furnace floor. However, the forward movement of the pusher has been limited by reason of the presence of the stationary run-off table. As a result, a portion of the furnace near the discharge end has been inaccessible to the pusher bar. Billets have therefore had to be rolled across this area by hand. Large billets occasionally require the efforts of at least four men for rolling them across this small area and into alignment with the discharge ram.

I provide a furnace in which the discharge or roll-off table is mounted on trucks so that it can be pushed away from in front of the furnace as the pusher advances. This construction permits the pusher bar to have access to substantially the entire floor surface of the furnace and eliminates the need for man power to advance the billets through the last portion of the furnace.

The roll-off table is mounted on a truck which is positioned in the path of the advancing pusher. As the pusher moves into position to engage the truck carrying the roll-off table, the latter is moved ahead of the pusher. In one form of the invention the truck carrying the roll-off table is coupled to the pusher so that the pusher on receding from the discharge end of the furnace draws the roll-off table truck into position opposite the discharge ram, when it is uncoupled.

In another form of the invention, the truck carrying the roll-off table is mounted on a support or track extending at angle to the support or track for the pusher so that the advancing pusher shoves the truck for the roll-off table up an incline. Then as the pusher recedes, the roll-off table is automatically positioned in front of the discharge ram on account of the action of the force of gravity. Stop mechanism is provided for automatically positioning the roll-off table in the correct position relative to the discharge ram.

The accompanying drawings illustrate certain present preferred embodiments of the invention, in which

Figure 1 is a plan view, partially in section, of a furnace and operating mechanism embodying my invention;

Figure 2 is a similar view of a portion of the furnace and operating mechanism on an enlarged scale;

Figure 3 is a side elevational view of the structure shown in Figure 1;

Figure 4 is a plan view, partially in section, of a modified form of furnace structure and operating mechanism;

Figure 5 is a similar view on an enlarged scale of a portion of the furnace;

Figure 6 is a side elevational view of the structure shown in Figure 4; and

Figure 7 is an enlarged sectional detail view of a shock absorbing mechanism.

Referring to Figures 1 to 3, a billet furnace 2 is provided with a receiving rack 3 on which billets 4 are deposited by any form of conveying mechanism. A door 5 closes the end of the furnace. Skids 6 are mounted on the floor 7 of the furnace which is preferably made sloping. The skids 6 extend from the receiving end of the furnace toward the discharge end for a large portion of the length of the furnace. The length of the skids is such that the billets are well heated before they reach the ends thereof.

Beyond the ends of the skids the billets 4 roll and/or slide directly on the floor of the furnace in order to prevent the formation of dark or cold rings corresponding to their areas of engagements with the skids 6. Where skids extend throughout the entire length of the furnace, there is a tendency for the portions of the billets which engage the skids to remain cold, which condition is exhibited by the presence of dark spots or rings. The presence of such cold portions of the billets interferes with subsequent operations performed on the billets. As the floor 7 of the furnace is maintained at substantially a uniform temperature throughout its width, movement of the billets along the furnace on the floor avoids formation of such dark or cold areas on the billets. If desired, a portion 8 of the floor 7 beyond the ends of the skids may be inclined more steeply than other portions thereof. The discharge end portion 9 of the furnace is preferably substantially horizontal.

It is to be understood that the furnace 2 is provided with the usual pipe lines for supplying air and removing products of combustion, but as such operating parts are well known in the art, a detailed showing thereof has been omitted. The furnace 2 terminates in a chamber 10 which may constitute a portion of the combustion chamber, or a mixing chamber, as desired.

The front face of the furnace is provided with a number of doors 11 through which access of the interior of the furnace is had. The rear face is likewise provided with doors 12 which are usually smaller than the doors 11.

For advancing the billets 4 along the skids 6 and the floor 7 of the furnace, a pusher bar 14 is mounted on a pusher truck 15 movable along a track 17 extending in substantial parallelism with the forward face of the furnace 2. The pusher bar 14, as is well understood in the art, is mounted on the truck 15 in such manner that it is projectable through the doors 11 for engaging the billets 4. The pusher bar is also mounted on tracks 18 and 19 on the truck 15 so that it may be turned through an arc of a circle for better advancing the billets 4. A detailed showing of the pusher

bar 14 and truck 15 have been omitted from the drawings, as these parts are well known in the art. A support for the truck 15 in the form of a track 17 is preferably given a pitch corresponding substantially to the pitch of the floor 7. While I have illustrated the floor 7 as being inclined, it is to be understood that it may be made horizontal if desired. In the latter case the track 17 is also placed in a horizontal position.

The billets 4 are discharged from the furnace 2 with a longitudinal movement by a ram 20 insertable through a door 21 near the rear end of the furnace. The ram 20 engages the ends of the billets 4 and projects them longitudinally through a door 22 in the other face of the furnace onto discharge rollers 24. The discharge rollers 24 cooperate with other run-off rollers 25 mounted on a truck 26 which moves along the track 17. The rollers 25 constitute a run-off table for billets discharged from the furnace. Heretofore it has been customary to provide a stationary run-off table opposite the discharge door 22. With such a construction the pusher truck 15 has not been able to advance the entire length of the furnace due to the engagement between the end of the truck and the stationary roll-off table structure. By mounting the roll-off table on a truck which is disposed in the path of movement of the pusher truck 15, the pusher truck moves the truck carrying the run-off table out of the way while operating near the discharge end of the furnace.

By having the pusher bar accessible to the discharge end of the furnace, the hand labor which has heretofore been required to roll the billets across the hitherto inaccessible portion of the furnace floor is eliminated. In furnaces where the billets have had to be rolled and/or skidded across portions of the furnace floor by hand owing to the inaccessibility of the pusher bar, the services of a considerable number of workmen have been required.

A coupling 27 connects the pusher truck 15 and the truck 26 so that upon the withdrawal of the pusher truck, which is usually done under its own power, the truck carrying the roll-off table is positioned so that the rollers 24 and 25 are in alignment. It is to be understood that the truck 26 may be provided with braking mechanism, if necessary.

Referring to Figures 4, 5 and 6, wherein parts corresponding to parts shown in Figures 1, 2 and 3 have been given the same reference numerals with a prime suffix, the pusher truck 15' mounted on a track 17' engages a truck 26' carrying rollers 25' similar to the rollers 25 shown in the other embodiment of the invention. In this form of the invention, the truck 26' is mounted on a support in the form of a track 28 which slopes upwardly from its forward end which is slightly be-

5 yond a discharge door 22' in the furnace 2'.
 Bumpers 29 are attached near the end of the
 track 28 so that the truck 26' normally rests
 against the bumpers 29 at the lower end of
 the track. With this construction the truck
 10 15' advancing along the track 17' engages the
 truck 26' and moves it upwardly along the
 track 28. As the truck 15' recedes from op-
 15 posite the discharge door 14', the truck 26'
 rolls down the track under the influence of
 the force of gravity until it is stopped by the
 bumper 29. By properly positioning the
 bumper 29, the truck 26' is automatically
 brought to rest with the rollers 25' in align-
 20 ment with the rollers 24' without requiring
 the manipulation of a coupling connection
 between the two trucks.

To cushion the shock between the trucks
 20 and to provide a rolling engagement therein,
 the truck 15' is provided with an arm or
 bracket 30 supporting a spring 31 surround-
 ing a shank 32 carrying a roller 33.

25 While I have shown and described certain
 present preferred embodiments of the in-
 vention, it is to be understood that it may be
 otherwise embodied within the spirit of the
 invention and the scope of the appended
 claims.

I claim:—

30 1. A furnace structure comprising a fur-
 nace, movable means for advancing material
 in the furnace, means for discharging ma-
 terial from the furnace, and a run-off table
 35 movable with the material advancing means
 during a portion of the movement of the lat-
 ter.

40 2. The combination with a furnace and
 discharge mechanism therefor, of a gravity
 positioned run-off table movable along a
 track, the track sloping upwardly toward the
 exit end of the furnace.

45 3. A furnace structure comprising an elon-
 gated furnace adapted for a rolling move-
 ment of billets therethrough, a track extend-
 ing along a face of the furnace means for ad-
 vancing billets in the furnace and movable
 50 along said track, means for ejecting billets
 from the furnace in the direction of their
 major axes, and truck mounted means for re-
 ceiving the billets discharged from the fur-
 nace, said receiving means being disposed in
 55 the path of the advancing means and movable
 therewith through a portion of its movement.

55 4. A furnace structure comprising a fur-
 nace having a sloping floor, means for ad-
 vancing material in the furnace, a track for
 supporting the advancing means, said track
 being substantially parallel to the floor of
 60 said furnace, a run-off table for material dis-
 charged from the furnace and a sloping track
 for supporting the run-off table, said last-
 mentioned track extending at an angle to the
 first-named track.

65 5. A furnace structure comprising a fur-

nace, means for discharging material from
 the furnace, a run-off table for receiving dis-
 charged material, a sloping track for sup-
 porting the run-off table and stop means on
 said track against which the run-off table
 70 normally rests for positioning the run-off
 table in co-operative relation to the discharge
 means.

6. A furnace structure comprising a fur-
 nace, means for advancing material length-
 wise through the furnace, a supporting track
 extending lengthwise of the furnace for the
 advancing means, a run-off table for receiv-
 ing material discharged from the furnace;
 means for discharging the material from the
 furnace to the run-off table, and a second
 track for supporting the run-off table, said
 75 tracks being so disposed that the material ad-
 vancing means during its travel will engage
 and move the run-off table.

7. In combination, a material housing
 chamber, means for advancing material in
 said chamber, a track for supporting the ad-
 vancing means, means for receiving material
 discharged from said chamber, a sloping
 80 track for supporting the receiving means, and
 stops on said track for positioning the receiv-
 ing means whereby, upon displacement, the
 receiving means returns to a predetermined
 85 position under the influence of the force of
 gravity.

8. A furnace structure comprising a fur-
 nace having a sloping surface, means for ad-
 vancing material along said surface, a sloping
 track extending in substantial parallelism to
 said floor for supporting said advancing
 means, a discharge device for said furnace, a
 truck mounted receiving device co-operating
 with said discharge device, a supporting
 track for said receiving device having an op-
 90 posite slope to the first-mentioned track and
 crossing said first-mentioned track near one
 end thereof whereby upon movement of the
 advancing means in one direction said receiv-
 ing means is raised during movement along
 95 its co-operating track, and means cooperating
 with the second-mentioned track for limiting
 the return movement of the receiving means
 during movement in a reverse direction un-
 der the influence of the force of gravity upon
 100 the withdrawal of the advancing means.

9. A furnace structure comprising a fur-
 nace having a sloping surface, means for ad-
 vancing material along said surface, a sloping
 support extending in substantial parallelism to
 said floor for supporting said ad-
 vancing means, a discharge device for said
 furnace, a truck mounted receiving device co-
 operating with said discharge device, a sup-
 port for said receiving device having an op-
 posite slope to the first-mentioned support
 and crossing said first-mentioned support
 near one end thereof whereby upon move-
 105 ment of the advancing means in one direction
 said receiving means is raised during move-

ment along its co-operating support, and means co-operating with the second mentioned tracks for limiting the return movement of the receiving means during movement of the receiving means in a reverse direction under the influence of the force of gravity upon the withdrawal of the advancing means.

10. A furnace structure comprising a furnace, a run-off table co-operating therewith, a sloping track for supporting the run-off table and bumpers on said track for automatically positioning the run-off table relatively to said furnace when said table is moved under the influence of the force of gravity.

15. 11. A furnace structure comprising a furnace having a discharge opening, movable means for progressively engaging and advancing material within and lengthwise of the furnace to a position adjacent said opening, means for discharging material through said discharge opening, and movable means normally aligned with said opening for receiving material discharged therethrough, said receiving means being movable by the material advancing means out of alignment with said opening during the portion of travel of the material advancing means effective for advancing material to a position adjacent said opening.

20. 12. A furnace structure comprising a furnace constructed for the longitudinal travel therethrough of material to be heated, said furnace having a charging opening adjacent one end, and a discharge opening adjacent the opposite end, a track extending along one face of the furnace, means movable along said track for advancing material lengthwise of the furnace from said charging opening to a position adjacent said discharge opening, a movable run-off normally aligned with said discharge opening for receiving discharged material from the furnace, and means for discharging the material through the discharge opening onto the run-off, said run-off being disposed in the path of travel of the material advancing means along said track and movable therewith and thereby during that portion only of its movement effective for moving material into a position adjacent said discharge opening.

25. 13. A furnace structure comprising a furnace having a charging opening adjacent one end and a discharge opening adjacent the opposite end, a track extending along one face of the furnace, means movable along said track for advancing material lengthwise of the furnace from said charging opening to a position adjacent said discharge opening, truck mounted means normally adjacent said discharge opening for receiving discharged material from the furnace, and means for discharging the material through the discharge opening onto the truck mounted means, said truck mounted means being disposed in the path of travel of the material

advancing means along said track and engageable therewith and movable thereby through the portion of movement of the material advancing means effective for advancing material to a position adjacent said discharge opening.

30. 14. A furnace structure comprising a furnace having a charging opening adjacent one end and a discharge opening adjacent the opposite end, a truck mounted pushing device for advancing material lengthwise of the furnace from said charging opening to a position adjacent said discharge opening, a truck mounted receiving device for receiving material discharged through said discharge opening, and means for discharging the material through the discharge opening onto the truck mounted receiving device, said devices being both adapted for movement adjacent a common face of the furnace and in overlapping paths whereby one device is engaged and moved by the other device during a predetermined portion only of the travel of such other devices.

35. 15. A furnace structure comprising a furnace having a charging opening and a discharge opening and constructed for the travel of material lengthwise of the furnace from one opening to the other, movable means for receiving material discharged through said discharge opening, means for discharging material through the discharge opening onto the receiving means, and movable means for advancing material lengthwise of said furnace from a position adjacent the charging opening to a position adjacent the discharge opening, said second mentioned movable means having a path of movement along substantially the entire length of said furnace and effective during a portion only of its travel for engaging and moving the receiving means out of its normal co-operative position relative to the furnace.

40. 16. A furnace structure comprising an elongated furnace having a charging opening adjacent one end thereof and a discharge opening adjacent the opposite end, a truck mounted receiving device normally occupying a position adjacent said discharge opening for receiving material discharged from the furnace therethrough, a ram for pushing the material from the furnace through the discharge opening onto the receiving device, a truck mounted pusher bar for advancing material lengthwise of the furnace from a position adjacent said charging opening to a position adjacent said discharge opening, said receiving device normally occupying an area through which said pusher bar must move in advancing material lengthwise of the furnace, and said pusher bar being accessible to substantially the entire floor surface of the furnace only upon displacement of said receiving device from said area.

45. 17. A billet furnace structure comprising

- an elongated furnace having a discharge opening, a truck mounted run-off table, means for discharging material through said discharge opening onto the run-off table, and
5 truck mounted pusher bar normally operatively disconnected from the run-off table and disposed on the same side of the furnace as the run-off table and movable into the through an area normally occupied by said
10 run-off table upon movement of said pusher bar, for moving material throughout substantially the entire length of the furnace and into a position where such material when so moved may be received by said run-off
15 table.

In testimony whereof I have hereunto set my hand.

REINHARDT DAAE.
